(57) **CLAIM**

The ornamental design for a wall art frame, as shown and described.

DESCRIPTION

FIG. 1 is a rear view of a wall art frame showing my new design in an assembled state;

FIG. 2 is front view thereof;

FIG. 3 is a front perspective view thereof;

FIG. 4 is a front perspective view thereof in a partially disassembled state;

FIG. 5 is a front perspective view thereof in a disassembled state;

FIG. 6 is a front view thereof, shown separately for completeness of illustration; and,

FIG. 7 is a front perspective view thereof.

The broken lines showing a level in FIG. 3 and a wall in FIG. 7 are included for the purpose of illustrating environmental structure that forms no part of the claimed design.

1 Claim, 7 Drawing Sheets
